BELL RINGING PUSH BUTTON

Jerome I. Rodale and Charles Leslie Smith, Jr.,
Allentown, Pa.

Application December 21, 1953, Serial No. 28,154

Term of patent 14 years

(Cl. D72—1)

To all whom it may concern:

Be it known that we, Jerome I. Rodale and Charles Leslie Smith, Jr., citizens of the United States, residing at Allentown, in the county of Lehigh and State of Pennsylvania, have invented a new, original, and ornamental Design for a Bell Ringing Push Button, of which the following is a specification, reference being had to the accompanying drawing, forming part thereof.

In the drawing:

Fig. 1 is a top view of a bell ringing push button showing our new design.

Fig. 2 is a side view of the push button shown in Fig. 1.

Fig. 3 is a perspective view of the push button.
We claim:

The ornamental design for a bell ringing push button, substantially as shown.
